OSCAR R. KENDALL AND LEMUEL C. KENDALL, OF GROTON, NEW HAMPSHIRE.

Letters Patent No. 88,306, dated March 30, 1869.

IMPROVEMENT IN CLAPBOARD-MACHINES.

The Schedule referred to in these Letters Patent and making part of the same.

To all whom it may concern:

Be it known that we, OSCAR R. KENDALL and LEMUEL C. KENDALL, both of Groton, in the county of Grafton, and State of New Hampshire, have invented new and useful Improvements in Clapboard-Machines; and we do hereby declare that the following is a full and exact description of the same, reference being had to the accompanying drawings, and to the letters of reference marked thereon.

This invention relates to certain improvements in clapboard and other sawing-machines, and consists mainly in the arrangement of the lever which operates the devices for changing the motion of the carriage, the construction being such that it may be automatically actuated by the carriage, or be operated by hand, as may be desired.

The details of construction, and the manner of operation, will be fully described hereinafter.

In the drawings—

Figure 1 represents a plan view of our improved machine, with the carriage removed.

Figure 2, a side elevation of the same, with a portion of the side broken away, to show the manner of adjusting the said frame.

Figure 3, a plan view of the carriage detached, and Figure 4, a side elevation of the same.

The same letters refer to identical parts in all the figures of the drawings.

To enable those skilled in the art to which our invention appertains, to make and use the same, we will now proceed to describe fully its construction and the manner of operating it.

A represents the main frame of the machine, which is strongly put together, in the usual form, and is supported upon the legs A' A'.

B represents a track, resting upon the side pieces of the frame, upon which runs the carriage C.

D represents the saw-frame, one end of which is securely attached to the legs of the frame A, as clearly shown in fig. 2, in such manner, however, as to permit the free end of the frame to have a limited motion.

This free end is provided with rack-bars d d, into which mesh gear-wheels e e, upon shaft E, which latter is provided with a ratchet and pawl, e', upon the outside of the frame A, and also has the hand-wheel, or crank E'. This hand-wheel should be marked with lines or figures, in such manner as to indicate the position of the saw-frame by means of its own position relative to a given point.

Within the saw-frame is hung, in suitable bearings, the arbor D', upon which is the saw D'.

Upon the arbor D' is also the pulley D³, from which a belt runs to pulley D⁴ upon a shaft placed at the lower end of the saw-frame.

D⁵ also represents a pulley, upon same shaft, by means of which motion is communicated from the drum under the mill. By means of these connections, motion is given to the saw when desired.

F represents a cross-bar, placed near the saw, to give stiffness to the frame.

F' represents the saw-guide, which is located before the saw, and is constructed of a curved piece of iron, as shown in fig. 1.

It is provided with the central piece f, which has the arms f' f', the upper parts of which are hinged, and provided with a screw, as shown.

These arms have a hole through them, in which is placed a pivot, or plug, b², against which the saw runs. These pivots may be made of round leather or raw hide, and should be, in size, a little larger than the holes in the arms, so that, by tightening the screws, they may be securely held.

G represents a small frame, located upon the outside of the main frame A, at about its centre, in which is hung the gearing for operating the carriage.

G' represents a large pulley, upon whose shaft, within the frame, is the small gear-wheel g, which latter meshes into the rack of the carriage C'.

G² represents a small pulley, upon whose shaft is the small gear-wheel g¹, which latter engages with the gear-wheel g².

This gear-wheel has, upon the same shaft, within the frame, the gear-wheel g³, which meshes into the rack of carriage C.

Between these pulleys is the friction-wheel G³, upon whose shaft, outside of frame G, is the pulley G⁴, which latter is connected, by belt, with pulley G⁵, upon a shaft at the back end of the machine. This shaft passes through to the inside of the frame, and is provided with a pulley, which connects, by means of a belt, with a pulley upon the saw-arbor.

The inner end of the shaft, upon which friction-wheel G³ is located, has its bearing in an upright bar, which is pivoted below the bearing, and is swung from side to side by means of the lever H, the two being united by a connecting-rod.

By moving the lever, when the mill is running, motion is communicated either to the large pulley, G¹, by which means the carriage is caused to move slowly forward against the saw, or to pulley G², in which case the carriage will be caused to move rapidly back from the saw.

h' represents a stop, which limits the motion of the lever in one direction, it being limited in the other by coming in contact with the end of frame G.

I I represent standards, rising from frame A, which are provided, at the upper end, with holes, in which play the rods I' I'.

These rods are provided, at their inner ends, with notches, in which rests the lever H, as shown. These rods have also the springs i i and adjustable stops i' i'.

C represents the carriage, which is provided with the adjustable head-block C, as shown. It has also the rack-bar and wheels, arranged in the ordinary manner.

Upon the side to which the rack-bar is attached, are placed, upon the outside of the frame, the pins c c' and blocks C' C', by means of which the lever H is operated, and the carriage is caused to move automatically back and forth, for, when the advancing carriage reaches the proper point, the pin c' strikes the stop i', and force

back the rod out of the way of lever H, and, immediately after the latter is struck by the block C³, and forced forward. This movement causes the friction-pulley below to bear against the small pulley G², instead of the large pulley, and the carriage is run rapidly back until the pin c strikes the stop i upon the other side, and the block C³ forces the lever in the opposite direction, when the direction of the movement is again changed.

The devices for setting the log for a new cut are nearly the same as ordinarily used.

O represents the stationary spur, and O¹, the revolving head, between which the log is hung.

The latter is operated by the bevel-gear wheels O² O³, as shown.

Upon the shaft of the latter is the ratchet-wheel O⁴, as shown, which is actuated by the pawl o on the weighted and pivoted arm o'.

P represents a shoe, attached to an adjustable standard rising from frame A, as shown. This shoe is made of considerable length, say twelve inches in an eighteen-foot machine, so that the same distance may be set off whether the carriage runs back the whole distance or not.

A pin is inserted back of the pivoted arm o', by which means its movement may be regulated. This wheel also may be marked off, so as to indicate the thickness of the board set off by a given movement.

The operation of these devices is as follows:

When the carriage has finished its entire backward movement, the upper end of arm o' strikes against the under side of shoe P, and is consequently carried backward, moving with it the wheel O⁴, by which means the log is revolved more or less, as the case may be. As the carriage moves forward again, the arm o', being cleared from the shoe, naturally assumes an upright position again, thus drawing back the pawl ready for the next movement. From this description, the manner of operating our machine will be easily understood.

The log having been properly adjusted, and the saw-frame having been set to cut the desired depth, the mill is put in motion. The entire operation is now automatically performed. The carriage moves forward slowly, and the log is cut. It then runs back rapidly, and the log is adjusted for a new cut. These movements may be continued until the log is entirely sawn.

Having thus fully described our invention,

What we claim, and desire to secure by Letters Patent of the United States, is—

The arrangement of the lever H, rods I, and springs i, as described, for the purpose set forth.

This specification, signed and witnessed, this 16th day of September, 1868.

OSCAR R. KENDALL.
LEMUEL C. KENDALL.
